UNITED STATES PATENT OFFICE.

EMIL CHARLES ADOLPH WOLTMANN, OF PLAINFIELD, NEW JERSEY.

LABEL-HOLDER FOR PIGEON-HOLES, &c.

SPECIFICATION forming part of Letters Patent No. 364,196, dated May 31, 1887.

Application filed March 15, 1887. Serial No. 230,972. (No model.)

To all whom it may concern:

Be it known that I, EMIL CHARLES ADOLPH WOLTMANN, a citizen of the United States, and a resident of Plainfield, in the county of Union and State of New Jersey, have invented certain new and useful Improvements in Label-Holders for Pigeon-Holes, &c., of which the following is a specification.

My invention relates to an improved form 10 of label-holder for use upon pigeon-holes, post-office boxes, compartments, shelves, &c., and other receptacles for holding papers or other articles, which are open at one end; and the object of the same is to supply a more perfect, 15 handsome, and durable method of labeling such receptacles than has heretofore been possible.

My invention will be best understood by reference to the accompanying sheet of drawings, in which—

Figure 1 is a front view of a pigeon-hole (with the lower portion broken away) with the label-holder attached; Fig. 2, a perspective view of the holder with the label-plate extended; Fig. 3, a perspective view of the holder with the label-plate pushed in, and Fig. 4 a plan view of the front extremity of the outer casing.

Similar letters refer to similar parts throughout the several views.

In the various views, A represents the outer casing or body of the holder, which is made of tin or any other convenient material in any convenient manner, and is provided with the 25 bent flanges *a a* at either side, of height sufficient to enable the plate to which the label-holding device proper or label-plate is attached to slide easily in and out. The bent portion of the flange is provided with any convenient 30 number of openings, by means of which the holder is screwed or nailed to the inner face of the upper wall of the pigeon-hole, box, &c., to which it is to be attached. The vertical portions of the flanges *a a* are provided at their 35 inner extremities with the longitudinal slots *s s*, in which the shoulders *s' s'*, formed upon the sliding piece, can move backward and forward.

A' is the sliding piece, to which the label 45 plate or holder proper is attached, and consists of a plate of metal or wood sufficiently

thin and of such dimensions that it will slide easily between the flanges *a a* in the casing A. This sliding piece is provided at its inner extremity with the shoulders *s' s'*, formed on it or 55 attached to it in any convenient manner, which extend through the slots *s s* in the flanges *a a* and prevent the plate *A'* from sliding a distance greater than the length of the slots. The outer extremity of the sliding piece *A'* is provided with a hinge, *h*, to which is attached the label plate or holder proper, B, which is made of metal or wood, &c., and is provided with the turned-up flanges or edges *b b*, or other 60 similar flanges for holding the label in position.

The body of the holder or casing A is cut away at its outer extremity in the form of a semicircle, C, so as to enable the plate B to be grasped between the thumb and fingers and 70 pushed into or pulled out of the casing A.

The casing A of the holder is attached to the inner face of the upper wall of the pigeon-hole, box, &c., which is to be labeled by means of screws or tacks *o' o'* passing through the 75 openings *o o*, or in any other convenient manner, so that the front face of the plate A shall be on a line with the front edge of the upper wall, as shown in Fig. 1.

When the holder is ready for use, the sliding 80 piece *A'* is drawn out by grasping the label-plate B by the fingers and allowing it to drop on the hinge *h* and hang over the forward edge of the plate A, as shown in Fig. 2. The slots *s s* should be, preferably, as long as the 85 label-plate B is high, so that when the same is displayed the hinge on the forward end of the sliding piece *A'* may not extend beyond the front edge of the casing A.

A label, of card-board, paper, &c., may be 90 inserted in the hanging plate B, containing any desired indorsement, in the manner shown in Fig. 1. Labels so inserted may be removed or replaced at pleasure without the use of tacks or mucilage. When the pigeon-hole or other 95 receptacle is to be closed, the plate B is raised, and is pushed, with the sliding piece *A'*, back into the space formed within the casing, so that it shall assume the position shown in Fig. 3, and thus be protected from the dust and kept 100 from becoming bent or broken.

It is obvious from the foregoing that the in-

vention may be of any convenient size, and may be fitted to all sizes of pigeon-holes or boxes without reference to the same being of thick or thin material; also, that the holder may be modified by dispensing with the casing A and providing simple runners on the upper surface of the pigeon-hole, in which the sliding piece A' can slide; but the construction above described will be found to be most economical and convenient. The holder may be attached, say, to a paper-case containing pigeon-holes made of such thin material that it is impossible to fasten labels upon the faces of the dividing partitions. By providing each pigeon-hole with this form of label-holder it is possible not merely to label each clearly, distinctly, and permanently, but also to change, rearrange, and modify the system of labels in the shortest possible time, and without injury to the partition-walls, as the labels are merely slipped in and out, and it is not necessary to use mucilage or tacks for attaching them. Moreover, the appearance of the case is not marred by the relabeling, as is invariably the case where this is attempted with the ordinary method of labeling. By sliding the holder back into the casing after using the pigeon-hole, the labels are protected from dust and space in the box or pigeon-hole is economized. By making the holder of japanned tin great economy in cost of construction is made possible, and very little space is occupied in the interior of the pigeon-hole.

I claim as my invention—

35 1. In a label-holder for pigeon-holes and similar devices, the combination, substantially as hereinbefore set forth, of a plate arranged

to slide upon the upper wall of the same, means for holding the same in position, substantially as described, and a plate, to which a label may be attached, hinged to the outer end of said plate, arranged to slide on the surface of the pigeon-hole with the sliding plate, substantially as described.

2. In a label-holder for pigeon-holes, the combination, substantially as hereinbefore set forth, of a plate arranged to slide in and out upon the upper wall of the pigeon-hole, means, substantially as described, for holding the same and allowing the same to be moved in and out upon the said upper wall, a plate of the same width hinged to its outer extremity for holding said label and arranged to slide in and out with said first plate, and flanges upon said label-plate to receive and hold a label. 50

3. In a label-holder for pigeon-holes and similar devices, the combination, with the upper inner surface of the same, of the casing A, with the flanges a a, and means, substantially as described, for attaching it to said upper surface, the sliding piece A', with shoulders s' s', sliding in the slots s s in said flanges, and the label-plate B, provided with the flanges b b, for receiving and holding the label, hinged to and sliding with the sliding piece, and the cut C in 65 the front face of the casing, for the purposes set forth.

Signed at New York, in the county of New York and State of New York, this 14th day of March, A. D. 1887.

EMIL CHARLES ADOLPH WOLTMANN.
